(57) **CLAIM**

The ornamental design for a flower hook, as shown and described.

DESCRIPTION

FIG. 1 is a perspective view of an flower hook showing our new design;

FIG. 2 is a top plan view thereof;

FIG. 3 is a front elevational view thereof;

FIG. 4 is a right side elevational view thereof, the left side elevational view being a mirror image;

FIG. 5 is a rear elevational view thereof;

FIG. 6 is a bottom plan view thereof;

FIG. 7 is a perspective view of a second embodiment of the design shown in FIG. 1;

FIG. 8 is a top plan view thereof;

FIG. 9 is a front elevational view thereof;

FIG. 10 is a bottom plan view thereof;

FIG. 11 is a right side elevational view thereof, the left side elevational view being a mirror image; and,

FIG. 12 is a rear elevational view thereof.

The dotted-line showing in the drawings illustrates environmental matter and forms no part of the claimed design.

CERTIFICATE OF CORRECTION

PATENT NO. : D631,334 S
APPLICATION NO. : 29/366419
DATED : January 25, 2011
INVENTOR(S) : Sheldon H. Goodman et al.

Page 1 of 4

It is certified that error appears in the above-identified patent and that said Letters Patent is hereby corrected as shown below:

Delete the title page and substitute therefore the attached title page showing the corrected description of figures and number of drawing sheets in patent.

On page 1 of the patent, at Section (57), the description should be amended to read as follows:

--FIG. 1 is a perspective view of a flower hook showing our new design;
FIG. 2 is a top plan view thereof;
FIG. 3 is a front elevational view thereof;
FIG. 4 is a right side elevational view thereof, the left side elevational view being a mirror image;
FIG. 5 is a rear elevational view thereof; and
FIG. 6 is a bottom plan view thereof.--

Delete Drawing Sheets 1-5 and substitute therefore the attached Drawing Sheets 1-2 consisting of Figs. 1-6.

Drawing FIGS. 7 through 12 are to be deleted from the patent.

Signed and Sealed this
Nineteenth Day of April, 2011

David J. Kappos
Director of the United States Patent and Trademark Office
